UNITED STATES PATENT OFFICE.

ALEXANDER HENRY LAKE, OF MARSHFIELD, WISCONSIN.

WEBBED HAND FOR SWIMMERS.

Application filed May 29, 1926. Serial No. 112,621.

This invention relates to a webbed hand for swimmers and more particularly to a glove-like device for application to the hand and providing between the fingers a web increasing the effective surface of the hand.

An important object of the invention is to provide a device of this character wherein the web is extended beyond the ends of the fingers to further increase the surface.

10 A more specific object of the invention is to provide novel and improved means for supporting the extended portions of the web.

A still further object of the invention is to provide a device of this character so constructed that the closing action of the hand is not interfered with.

20 A further object of the invention is to provide a device of this character wherein the palm surface of the glove when in extended position is cupped to more efficiently engage the surface of the water.

25 These and other objects I attain by the construction shown in the accompanying drawings, wherein for the purpose of illustration is shown a preferred embodiment of my invention and wherein:—

30 Figure 1 is a plan view of a webbed hand for swimmers constructed in accordance with one embodiment of my invention wherein the web is extended beyond the ends of the fingers;

35 Figures 2, 3, 4 and 5 are sections on the line 2—2, 3—3, 4—4, and 5—5 of Figure 1 respectively;

40 Figures 6 and 7 are views of the blanks from which the glove is constructed;

45 Figure 8 is a detail view of one of the triangular sections of cloth employed in connecting the edges of the notches to draw the same together;

50 Figure 9 is a perspective of one of the reinforcing elements;

Figure 10 is a perspective of the reinforcing element employed between the fingers;

55 Figure 11 is a plan view of a slightly modified glove;

Figure 12 is a perspective view of the reinforcing element employed with this type of glove.

50 Referring now more particularly to the drawings, the device is formed in front and back sections 10 and 11 stitched together about their edges, as at 12, and having further stitching 13 providing pockets for the 65 reception of the thumb and fingers of the wearer. The sections 10 and 11 are of such

length that they project beyond the outer ends of the pockets formed for the reception of the fingers and the pockets are so formed that when the hand is engaged therein, the 60 fingers are well spaced. In the spaces formed between the finger pockets, indicated at 14, reinforcing elements 15 are secured, these elements being preferably in the form of wires, each having their ends formed with 65 an eyed loop 16 through which stitching 17 may be directed to secure the reinforcing element in position. These reinforcing elements serve to support the projecting portions 18 of the palm and back sections of the 70 glove and to maintain the same in line with the fingers and the reinforcing elements have their inner ends arranged in approximate alignment with the second joint of the fingers of the wearer when the hand is inserted 75 in the glove, thus permitting bending of the fingers at this joint.

Further reinforcing elements 19 are provided, these elements being each in the form of a piece of wire bent to provide arms 20, 80 21 extending at opposite sides a finger pocket 14 and having the bight between these arms extended well beyond the end of this finger pocket, so that it likewise serves to support the extended portion 18 of the web. This 85 bight portion and the ends of the arms are preferably provided with eyes 22 through which stitching may be directed to secure the reinforcing element in position and the ends of the arms adjacent the bight portion are 90 curved, as at 23, so that the reinforcing elements, when viewed in side elevation, have a concave face opposing the palm section of the glove. This causes the edge of the flange to be thrown upwardly of the 95 plane of the hand with the result that the palm surface is concaved and has a more efficient engagement with the water when passing therethrough. It will be understood that the reinforcing elements hereinbefore 100 referred to are stitched between the front and back sections 10 and 11 of the glove.

The portion of the glove aligning with the palm of the hand is of such width that it projects beyond that side of the palm aligning with the little finger and this projecting portion is supported by a reinforcing element 24 similar to the reinforcing elements 15 and secured to the palm section 10 of the glove at the inner surface thereof. The material is preferably stitched to this palm section at the inner face thereof, as indicated 110

at 25, to provide a pocket within which this reinforcing element is arranged. At the wrist, each of the sections 10 and 11 has associated therewith an elastic 26 for tightening the wrist section upon the wrist of the wearer.

I have found that in constructing a glove of this character, when the fingers of the wearer are in position therein, there is slack material between the fingers of the hand and in order to remove this and provide a smooth finish for the glove, I remove from between each finger stall a V-shaped section, the edges of which are drawn together and securely fastened by applying to the front and rear sections triangular pieces 27. A glove produced in this manner provides a greatly extended water engaging surface, which is relatively rigid and in which a great portion of the strain is placed at the bases of the fingers instead of at the tips thereof, as in the ordinary swimming aid. The cupping of the palm section further assists in relieving strain upon the fingers and increases the efficiency of the device in its engagement with the water.

In the form shown in Figure 11, the web is not extended beyond the ends of the fingers. In this construction, the reinforcing elements 28 employed are more clearly shown in Figure 12, each consisting of a U-shaped element having its arms 28 adjacent their bight ends curved to cause cupping of the palm, as in the construction above described and the ends of the arms provided with eyes 29 through which anchor stitching may be directed. While a construction of this character does not give the surface area of the construction originally described, the formation of the webs between the fingers and the cupping of the palm materially increase the efficiency of the glove. In this construction, as in the original construction, the ends of the arms of the reinforcing elements are terminated at the first joint of the finger. In this construction, the reinforcing elements 15 are dispensed with.

Since the constructions hereinbefore set forth are obviously capable of a certain range of change and modification without materially departing from the spirit of the invention, I do not limit myself to such specific structures except as hereinafter claimed.

55 I claim:—

1. A webbed hand for swimmers comprising a member having a pocket to receive the hand and spread fingers of the wearer and providing a web between the fingers and extended beyond the ends of the fingers and reinforcing elements for the extended portions of the web and extending between the finger receiving portions of the pocket, the inner ends of said reinforcing elements terminating in approximate alignment with

that portion of the pocket in which the first joints of the fingers are located.

2. A webbed hand for swimmers comprising a member having a pocket to receive the hand and spread fingers of the wearer and providing a web between the fingers and extended beyond the ends of the fingers and reinforcing elements for the extended portions of the web and extending between the finger receiving portions of the pocket, said 75 reinforcing elements being curved to cup the extended portions of the web at the palm side thereof.

3. A webbed hand for swimmers comprising a member having a pocket to receive the hand and spread fingers of the wearer and providing a web between the fingers and extended beyond the ends of the fingers and reinforcing elements for the extended portions of the web extending between the finger receiving portions of the pocket, said member being formed in two complementary sections between which said reinforcing elements are arranged.

4. A webbed hand for swimmers comprising a member having a pocket to receive the hand and spread fingers of the wearer and providing a web between the fingers and extended beyond the ends of the fingers and reinforcing elements for the extended portions of the web extending between the finger receiving portions of the pocket, said member being formed in two complementary sections between which said reinforcing elements are arranged, each of said sections between the finger receiving sections of the pocket having V-shaped sections removed therefrom, the edges of the openings thus provided being drawn together and secured.

5. A webbed hand for swimmers comprising a member having a pocket to receive the hand and spread fingers and providing a web between the fingers and reinforcing elements for the perimeter of the webbed hand having portions extending between the finger receiving portions of the pocket, the inner ends of said reinforcing elements terminating in approximate alignment with that portion of the pocket in which the first joints of the fingers are located.

6. A webbed hand for swimmers comprising a member having a pocket to receive the hand and spread fingers and providing a web between the fingers and reinforcing elements for the perimeter of the webbed hand having portions extending between the finger receiving portions of the pocket, the inner ends of said reinforcing elements terminating in approximate alignment with that portion of the pocket in which the first joints of the fingers are located, the outer ends of said reinforcing elements being curved to cup the palm surface of the hand.

7. A webbed hand for swimmers comprising a member having a pocket to receive

the hand and spread fingers of the wearer and providing a web between the fingers and reinforcing elements for the web and extending between the finger receiving portions of the pocket, said reinforcing elements being curved to cup the web at the palm side thereof.

8. A webbed hand for swimmers comprising a member having a pocket to receive the hand and spread fingers of the wearer and providing a web between the fingers and reinforcing elements for the web extending between the finger receiving portions of the pocket, said member being formed in two complementary sections between which said reinforcing elements are arranged, each of

9. A webbed hand for swimmers comprising a member having a pocket to receive the hand and spread fingers of the wearer and providing a web between the fingers and reinforcing elements for the web extending between the finger receiving portions of the pocket, said member being formed in two complementary sections between which said reinforcing elements are arranged, each of said sections being the finger receiving sections of the pocket having V-shaped sections removed therefrom, the edges of the openings thus provided being drawn together and secured.

In testimony whereof I hereunto affix my signature.

ALEXANDER HENRY LAKE.
